DESIGN FOR AN ACCORDION

Robert Rosciani, Chicago, Ill., assignor to Italo-American Accordion Manufacturing Company, Chicago, Ill., a partnership composed of Antonio Petromilli, Daniel Petromilli, Ovidio Piatanesi, Demo Piatanesi, Bramante Piatenesi, and Robert Rosciani

Application March 24, 1937, Serial No. 68,388

Term of patent 7 years

To all whom it may concern:

Be it known that I, Robert Rosciani, a citizen of the United States, residing at Chicago, Cook County, Illinois, have invented a new, original, and ornamental Design for an Accordion, of which the following is a specification, reference being had to the accompanying drawing forming part thereof, showing my new design.

The dominant feature of my design resides in the portions illustrated in solid lines.

I claim:

The ornamental design for an accordion as shown and described.

ROBERT ROSCIANI.
